NOZZLE CONSTRUCTION FOR REFRIGERATED
CABINETS

Sterling Beckwith, Libertyville Township, and Robert E. Vogel, Deerfield, Ill., assignors to Dual Jet Refrigeration Company, Chicago, Ill., a corporation of Illinois

Filed Dec. 9, 1963, Ser. No. 329,047
11 Claims. (Cl. 98—36)

This invention relates to improved constructions for use in the handling of two or more air curtains which are to be moved in side-by-side relationship. Specifically, the invention is directed to novel constructions which are designed to effect the character of the moving air curtains whereby they can be moved in a highly efficient manner.

The instant invention will be described with reference to refrigerated cabinet constructions. In such constructions, air curtains are moved across an access opening for the cabinets and the character of the curtains is important with regard to efficient operation of the construction. It will be understood, however, that the nozzles employed herein can be utilized for the handling of air streams in other constructions where the necessary characteristics of the streams are similar to the characteristics required of streams in refrigerated cabinets.

In an application of Hagen et al., Serial No. 54,077, filed September 6, 1960, and in the issued Simons Patent No. 2,862,369, there are described refrigerated display cabinets which are provided with access openings exposed to the atmosphere while still being capable of maintaining the contents in a refrigerated state. Loss of refrigeration from the enclosed space through the access opening is reduced in a highly effective manner in these constructions by the use of a gaseous, preferably air, curtain which is continuously advanced across the open side from one edge of the opening to the opposite edge. The air curtain in these constructions is adapted to be formed of adjacent panels of air, with the innermost panel comprising a refrigerated cold air panel, and with one or more outer panels having temperatures approaching the ambient temperature. It has been found that it is desirable to recirculate the inner cold air panel and to provide means for circulating the adjacent guard panels, to conserve the refrigeration and to maintain the enclosed space in a satisfactory refrigerated state.

In these constructions there are described assemblies which include nozzles extending across the bottom edge of the access opening to direct the air panels upwardly across the opening towards inlets which extend across the top side of the access opening. As an alternative, the nozzles are located across the upper edge for projecting the air panels downwardly toward inlets arranged across the bottom edge. It is also contemplated that the air nozzles be located across one of the lateral edges of the opening for directing the corresponding air panels across the opening toward inlets in the opposite edge. Because of the more desirable effect of gravity on the higher density cold air, it has been found preferable to provide the air curtain with a downward movement from nozzles across the top to inlets across the bottom. The following description will refer to this preferred construction, although it will be understood that the concepts to be described are also applicable to other directions of flow.

In the use of cabinets of the type described, it is, of course, desirable to provide maximum efficiency insofar as the amount of power consumed is concerned. In refrigeration systems of this type, the consumption of power is primarily due to the refrigeration of the moving air streams which pass over the access opening for the cabinet. To a somewhat lesser degree, power is con-

2

sumed during defrosting cycles and due to the driving of fans for circulation of the streams. As far as the refrigeration of the streams is concerned, a major factor contributing to the amount of power consumption is the loss of refrigeration (or intake of heat) through the access opening.

Loss of refrigeration can be attributed to a substantial degree to turbulence which is set up between moving air streams and still air adjacent the moving air streams. Specifically, it has been found that the movement of a stream adjacent still air or adjacent a stream moving at a substantially different speed will create turbulence and will result in a "whipping" action. The moving streams of air when characterized by such action, move out of their intended paths periodically, and large masses of the air can be completely lost insofar as the circulating streams are concerned. Where these masses are refrigerated, the natural result is to increase the load on the refrigerating means for the cabinet so that the loss of refrigeration can be accommodated.

It is an object of this invention to provide a refrigerated cabinet construction which includes means for decreasing the amount of power consumption necessary to achieve a desired level of refrigeration.

It is a more particular object of this invention to provide a cabinet construction of the type described which is provided with unique outlet nozzles for passing refrigerated streams across an access opening, which nozzles are effective to reduce the turbulence set up between the streams and the ambient air to thereby increase the efficiency of operation of the cabinet.

These and other objects of this invention will appear hereinafter and for purposes of illustration but not of limitation, specific embodiments of the invention are shown in the accompanying drawings in which:

FIGURE 1 is an elevational view partly cut away of a refrigerated cabinet characterized by the features of this invention;

FIGURE 2 is an enlarged fragmentary view in section illustrating one form for the nozzle constructions of this invention;

FIGURE 3 is an enlarged fragmentary view in section illustrating an alternative nozzle construction;

FIGURE 4 is an enlarged fragmentary view in section illustrating an additional form of a nozzle construction;

FIGURE 5 is an enlarged fragmentary view in section illustrating a further alternative form of nozzle construction;

FIGURE 6 is an enlarged fragmentary view in section illustrating another form of nozzle construction;

FIGURE 7 is a fragmentary plan view of air passage means suitable for use in the construction of FIGURE 6; and

FIGURE 8 is a fragmentary view of an alternative form of air passage means suitable for use in the construction of FIGURE 6.

As discussed above, the improvements of this invention are directed to constructions which employ air curtains moving in side-by-side relationship in an unconfined manner. These improvements are specifically directed to refrigerated enclosures of the type which define an access opening in one wall whereby communication with the space within the enclosure can be accomplished. The enclosures or cabinets of this invention are provided with a plurality of nozzles arranged in side-by-side

relationship across one edge of an access opening and corresponding inlets are located across the opposite edge of the access opening. The inner nozzles and inlets are provided for the passage of a refrigerated stream across the access opening while the adjacent outer nozzles and inlets circulate progressively warmer air panels. The inner refrigerated stream is circulated through a passage

having refrigeration coils located therein and one or more of the outer adjacent streams may also be refrigerated.

In accordance with the practice of this invention, it has been found that if means are provided for controlling the circulation of the air panels in a certain manner, then a greater degree of efficiency, insofar as loss of refrigeration is concerned, can be obtained.

Specifically, it has been found that reduction in turbulence can be achieved by providing for control of the speed of circulation of the air streams. Thus, if the portions which contact the relatively still ambient air move at a slower speed than other portions of the stream, reduction in turbulence can be achieved.

The specific constructions of this invention which are employed for achieving the desired results comprise nozzles having unique designs. Honeycomb material is preferably employed for the construction of these nozzles since this material is available in a form which is suitable for the purposes of this invention. Thus, this material is characterized by a plurality of small passages aligned in parallel relationship and the material is also adapted to be provided in a greater number of shapes and sizes. It will be understood, however, that the provision of other constructions which have the same characteristics as honeycomb materials is contemplated for use in accordance with this invention.

The nozzles employed in the cabinets of this invention are designed whereby they will affect the rate of movement of the streams of air which pass out of the nozzles for movement across the access opening of the cabinet. Specifically, the nozzles are designed whereby the outer portions of the streams which contact the ambient air, or which contact slower moving air streams, are passed across the opening at a relatively low speed to effect the desired decrease in turbulence.

The nozzle constructions are also capable of affecting the speed of the air streams whereby approximately the same rate of movement at the interface of adjacent panels can be maintained. This capability of the nozzle constructions serves to maintain a high degree of laminar flow in the air streams which also results in a more uniform temperature condition in the adjacent streams. This condition has also been recognized as a means for increasing the efficiency of operation.

The accompanying drawing illustrates in FIGURE 1 a refrigerated cabinet 10 having nozzle means characterized by the features of this invention. The cabinet 10 includes a top wall 12, a bottom wall 14, a back wall 16 and a front wall 18. The front wall 18 defines an opening 20 which provides access to the interior 22 of the refrigerated cabinet. An inner wall 24 defines the extent of the refrigerated space.

A partition 26 is formed to define an inner passage 28 and an outer passage 30 in the construction. The inner passage 28 carries a refrigerating means 32 and a circulating fan 34 provides for movement of air past the refrigerating means and through the passage 28. A similar circulating fan 36 is provided for the outer passage 30.

Inlets 38 are provided for each of the passages 28 and 30. The streams 40 and 32 which cross the access opening pass into these inlets and are driven through the passages to outlet nozzles 44 and 46. Screens may be included over the inlets 38 to prevent entry of insects or other foreign material into the passages.

Specific forms for the nozzle constructions of this invention are shown in FIGURES 2, 3, 4, 5, 6, 7 and 8. In each, the nozzle construction 46 provided for the inner passage 28 comprises a honeycomb section having a plurality of aligned passages extending parallel to the walls which define the passage 28 beyond the corner 48. In the particular embodiment shown for the nozzles 46, the edges 50 of the nozzles begins at a point below the wall 52 which defines the lower extent of the pas-

sage 28. The stream of air in the passage 28 will be preferentially directed to the outer passages of the nozzle 46 by reason of this arrangement. It has been found that the inner portions of the stream 42 which contact the relatively still air within the cabinet move more slowly than the outer portions of this stream. This arrangement tends to reduce the possibility of turbulence between this inner stream and the air within the cabinet.

In the modification shown in FIGURE 2, the nozzle for the outer stream is formed in two sections 54 and 56. The upper section 54 comprises a generally triangular member having the hypotenuse thereof extending on a line between the edges 58 and 60 which define the corners in the passage 30. The base of the upper section 54 is in a horizontal position; and, therefore, the passages in the section 54 are at an acute angle with respect to the side walls which define the passage 30.

The lower section 56 comprises a plurality of passages which are aligned in a parallel relationship with respect to the side walls. It will be appreciated that streams of air passing through the section 54 will be preferentially directed toward the inner passages in the section 56. With this arrangement, a lower speed is achieved in those portions of the air issuing from the outer passages and, accordingly, a decrease in turbulence with respect to the ambient air can be realized.

In the construction shown in FIGURE 3, two sections 62 and 64 are also provided for forming the nozzle of the outer stream. In this embodiment, the passages in the honeycomb sections are all arranged in a parallel relationship; however, slower movement in the outer portions of the outer stream is achieved because of the curvilinear character of the section 62. The more pronounced curvature which characterizes this section at the inner portions thereof causes this section to pick up greater amounts of air in these inner portions. A slower movement then results with respect to outer portions of the stream and, again, a reduction in turbulence can be achieved.

In the modification shown in FIGURE 4, the outer stream must pass through a nozzle 66 which is substantially larger than the nozzle 46. The longer passages in the nozzle 66 result in a greater drag on the air passing therethrough. As a result, the speed of the outer stream will tend to be slower than the speed of the adjacent inner stream. Furthermore, the angular disposition of the top edge 68 of the nozzle 66 provides for longer nozzle passages for carrying the outer portions of the stream 40 while the inner passages of the nozzle become progressively smaller. The outer portions of the air stream 40 are, therefore, subjected to a greater drag and, accordingly, these outer portions will have a lesser tendency to create turbulence.

The construction shown in FIGURE 5 employs louver means 70 which is situated in the passage 30 in advance of nozzle 72. It will be noted that each of the elements 74 which define the louver means is directed at an angle whereby air in the passage will be forced inwardly with respect to the cabinet enclosure. Each of these elements 74 extends the entire length of the cabinet whereby the channels defined between the elements will also extend across the cabinet. It is contemplated that reenforcing means can be provided at one or more intermediate points between the adjacent elements to provide a substantially rigid structure.

The louvered arrangement illustrated acts to direct air in the passage 30 toward the inner side of the honeycomb. This has the effect of reducing the rate of movement of the air in the outer portion which is exposed to the ambient air.

The arrangement shown in FIGURE 6 comprises a combination of screen elements 76 and means 78 which defines openings 80 for passage of air to nozzle 82. As in the previous cases, the arrangement for effecting the characteristics of the air is provided in the passage 30.

A plan view of the means 78 shown in FIGURE 6 is illustrated in FIGURE 7. As shown therein, a plurality of slats 84 are provided in spaced apart relationship whereby the openings 80 will be defined therebetween. It will be noted that the openings become progressively larger as they occur from the outer portion of the means 78 to the inner portion thereof. This arrangement also has the effect of directing a major portion of the air at the inner side of the passage 30 while lesser portions thereof pass in the portion of the outer stream adjacent the ambient air.

FIGURE 8 illustrates a proposed modification 78' wherein progressively larger openings 80' approximately correspond in function to the openings 80. It will be apparent that this arrangement will affect the air stream in substantially the same manner as described above. The screen 76, which may be conventional window screen, has been found to be a desirable addition since it has the effect of breaking up the air so that it will not pass through the outlet nozzles in the form of jets. This results in a smoother gradient of air speed across a given panel as will be discussed with reference to FIGURE 2.

FIGURE 2 illustrates diagrammatically the results which can be achieved with the nozzle constructions of this invention. In this diagram, the horizontal axis corresponds to the width of the nozzles employed in the construction. When the speed of a stream across this width is plotted as illustrated, the desirable character of the streams issuing from the nozzles will be appreciated. With respect to the nozzle sections 54 and 56 in FIGURE 2, the X designations on the diagram are employed to plot the speed of the stream across its width. It will be noted that a relatively slow air velocity is achieved in the outer portions of the stream while a relatively high air velocity is achieved in the inner portions. The circles plotted along with the X on the diagram illustrate the findings with the upper section 54 removed. As noted, the outer portions of the stream actually move at a higher rate than the inner portions. The greater possibility of turbulence with this arrangement will be obvious.

The right-hand section of the diagram illustrates the affect of the nozzles 46 on the speed of the refrigerated streams. As noted, the lowest speed is achieved in the innermost portions of the stream and, therefore, a decrease in turbulence in this region can be accomplished.

Where the outer nozzles are concerned, it will be understood that these nozzles are to be employed in any position where the streams passing therethrough will contact other air having a substantially lower rate of movement; or in the case of ambient air, having substantially no movement. The nozzle constructions may be utilized in cabinets of the type described by Beckwith et al., in application Serial No. 247,245, filed December 26, 1962, and entitled Refrigerated Cabinet With Circulating Air Panels. In this construction, an outer stream which was not powered by any mechanical circulating means was included. The nozzles of this invention could be employed for the intermediate passages in such a construction.

From the above description, it will be apparent that constructions have been described which serve to affect the characteristics of moving air streams in a desirable fashion. The constructions described accomplish a relatively low discharge air velocity in the outer edge of the outer guard stream. At the same time, these constructions accomplish relatively high velocity at the interface between the refrigerated stream and the guard stream. It has been found that the use of arrangements of the type described will greatly improve the operating efficiency of refrigerated enclosures. The arrangement permits the use of larger air curtains to thereby increase the size of an access opening. A construction employing these arrangements has less compressor running time, less build-up of frost and also reduces air spill-out so that a person standing in front of the freezer will not be annoyed by contact with a cold air stream. In considering the above advantages, it will be apparent that similar advantages are

available in other construction employing the units of this invention.

It will be understood that various changes and modifications may be made in the constructions illustrated herein which provide the characteristics of this invention without departing from the spirit thereof particularly as defined in the following claims.

That which is claimed is:

1. In a refrigerated cabinet of the type which defines an access opening in one wall communicating an otherwise enclosed space with the ambient atmosphere, and which is provided with a plurality of air inlets and a plurality of air nozzles, said inlets and nozzles extending in side-by-side relationship across opposite edges of said access opening, passages defined by said cabinet communicating each of the corresponding inlets and nozzles, refrigeration means disposed in the innermost one of said passages to refrigerate at least the innermost stream, and circulating fans located in said innermost passage and in an immediately adjacent outer passage, the improvement wherein said nozzles comprise honeycomb sections, the honeycomb section for said outer stream including an outer portion adapted to progressively reduce the speed of the outer portion of the air stream passing therethrough whereby the extreme outer portion of the stream crossing said access opening sets up a minimum of turbulence when contacting the ambient air, said honeycomb section for said outer stream including two spaced-apart upper and lower portions, the passages through the lower portion being positioned substantially parallel to the side walls of the passage confining the honeycomb section, and the passages through said upper portion being directed inwardly at an acute angle with respect to said first mentioned passages.
2. A cabinet in accordance with claim 1 wherein the upper portion of said honeycomb section is fixed in position at the upper corner defined by the passage for said adjacent outer stream, and wherein said upper portion has a generally triangular cross section with the hypotenuse thereof extending angularly inwardly at said corner and with the base thereof being disposed approximately horizontally.
3. In a refrigerated cabinet of the type which defines an access opening in one wall communicating an otherwise enclosed space with the ambient atmosphere, and which is provided with a plurality of air inlets and a plurality of air nozzles, said inlets and nozzles extending in side-by-side relationship across opposite edges of said access opening, passages defined by said cabinet communicating each of the corresponding inlets and nozzles, refrigeration means disposed in the innermost one of said passages to refrigerate at least the innermost stream, and circulating fans located in said innermost passage and in an immediately adjacent outer passage, the improvement wherein said nozzles comprise honeycomb sections, the honeycomb section for said outer stream including an outer portion adapted to progressively reduce the speed of the outer portion of the air stream passing therethrough whereby the extreme outer portion of the stream crossing said access opening sets up a minimum of turbulence when contacting the ambient air, said honeycomb section for said outer stream including two spaced-apart upper and lower sections, said upper section being fixed at a corner defined by the outer passage for said outer stream and wherein the passages defined in both portions of said honeycomb section are approximately parallel with respect to each other.
4. A cabinet in accordance with claim 3 wherein the upper surface of said upper section is curvilinear to the extent that a greater exposure to said outer stream is presented by the inner passages of said upper section whereby the speed of the inner portions of said outer stream exceeds the speed of the outer portions thereof.
5. In a refrigerated cabinet of the type which defines an access opening in one wall communicating an other-

wise enclosed space with the ambient atmosphere, and which is provided with a plurality of air inlets and a plurality of air nozzles, said inlets and nozzles extending in side-by-side relationship across opposite edges of said access opening, passages defined by said cabinet communicating each of the corresponding inlets and nozzles, refrigeration means disposed in the innermost one of said passages to refrigerate at least the innermost stream, and circulating fans located in said innermost passage and in an immediately adjacent outer passage, the improvement wherein said nozzles comprise honeycomb sections, the honeycomb section for said outer stream including an outer portion adapted to progressively reduce the speed of the outer portion of the air stream passing therethrough whereby the extreme outer portion of the stream crossing said access opening sets up a minimum of turbulence when contacting the ambient air, said honeycomb section for said adjacent outer stream defining substantially longer passages than the honeycomb section for the innermost stream whereby a greater drag is presented by said outer honeycomb section to effect a reduced speed in the outer stream.

6. A cabinet in accordance with claim 5 wherein the passages defined by said outer honeycomb section gradually increase in length in an outward direction whereby the outer portions of the outer stream passing therethrough are subjected to a greater drag than the inner portions of said stream.

7. In a construction of the type defining an open side and including air inlet means and a plurality of air nozzles extending in side-by-side relationship across opposite edges of said open side, passages defined in said construction communicating each of the corresponding inlets and nozzles, and circulating means located in at least one of said passages for driving air streams through said passages and across said open side between corresponding inlets and nozzles, said air streams crossing said open side in side-by-side contacting relationship, the improvement comprising means for controlling the velocity of the air streams issuing from said nozzles, said last mentioned means providing for maximum velocity in said air streams at the interface thereof and for progressively decreasing velocity toward the outer edges of said air streams, said means for affecting the velocity of the air streams comprising elements in the outer passage of said construction located adjacent to and upstream of the nozzle for said outer passage, said elements operating to direct a maximum amount of air toward the interior portion of said outer stream to effect a maximum speed of this air at said interface.

8. In a refrigerated cabinet of the type which defines an access opening in one wall communicating an other-

wise enclosed space with the ambient atmosphere, said cabinet being provided with a plurality of air inlets and a plurality of air nozzles, said inlets and nozzles extending in side-by-side relationship across opposite edges of said access opening, passages communicating each of the corresponding inlets and nozzles, refrigeration means disposed in at least the innermost one of said passages to refrigerate at least the innermost stream passing through said passages and across said access opening, and circulating means included in said innermost passage and in an adjacent outer passage for moving the streams of air through said passages, the improvement comprising means for controlling the velocity of the air streams as they issue from said nozzles, said last mentioned means comprising elements positioned in said passages for contact with the streams passing therethrough and operating to provide a maximum velocity at the interface between the streams moving across said access opening with progressively decreasing velocity toward the outer edges of said streams.

9. A cabinet in accordance with claim 8 wherein the means for controlling the velocity of the air streams comprise louvers extending across the passage confining the outermost stream, said louvers being located adjacent to and upstream of the nozzle for said outermost stream, and air channels defined by said louvers directed downwardly and inwardly toward said last mentioned nozzle whereby faster moving portions of the outermost air stream are provided in the innermost sections thereof.

10. A cabinet in accordance with claim 8 wherein the means for controlling the velocity of said air streams comprise elements extending across the passage confining the outermost air stream, said elements being located adjacent to and upstream of the nozzle for said outermost passage, said elements defining openings extending across said passage with said openings being progressively larger toward the inner portions of said passage whereby a greater speed is produced in the innermost portions of the air stream in the outermost passage.

11. A cabinet in accordance with claim 10 wherein screens are located immediately upstream of said elements.
